US00D721716S

(12) **United States Design Patent**
Roberts et al.

(10) **Patent No.:** US D721,716 S
(45) **Date of Patent:** ** Jan. 27, 2015

(54) **DISPLAY SCREEN OR PORTION THEREOF
WITH GRAPHICAL USER INTERFACE**

(71) Applicant: **Apple Inc.**, Cupertino, CA (US)

(72) Inventors: **Samuel Morgan Roberts**, Santa Cruz, CA (US); **Randall Ubillos**, Los Altos, CA (US)

(73) Assignee: **Apple Inc.**, Cupertino, CA (US)

(**) Term: **14 Years**

(21) Appl. No.: **29/447,931**

(22) Filed: **Mar. 7, 2013**

(57) **CLAIM**

The ornamental design for a display screen or a portion thereof with graphical user interface, as shown and described.

DESCRIPTION

The FIGURE is a front view of a display screen or portion thereof with graphical user interface showing our new design. The dashed broken lines around the FIGURE show a display screen or portion thereof that form no part of the claimed design. The dot-dash lines in the FIGURE and the areas within the dot-dash lines show portions of the graphical user interface that form no part of the claimed design.
